UNITED STATES PATENT OFFICE.

CHARLES S. BIRD AND JOHN B. HANSCOM, OF EAST WALPOLE, MASSACHUSETTS, ASSIGNORS TO F. W. BIRD AND SON, OF EAST WALPOLE, MASSACHUSETTS, A FIRM COMPOSED OF CHARLES S. BIRD.

PACKAGE.

SPECIFICATION forming part of Letters Patent No. 694,304, dated February 25, 1902.

Application filed January 25, 1902. Serial No. 91,232. (No model.)

To all whom it may concern:

Be it known that we, CHARLES S. BIRD and JOHN B. HANSCOM, citizens of the United States, residing at East Walpole, in the county 5 of Norfolk and State of Massachusetts, have invented certain new and useful Improvements in Packages, of which the following is a specification, reference being had therein to the accompanying drawings.

10 This invention relates to improvements in packages.

The invention more particularly relates to improvements in combination-packages in which sheet or strip material adapted or intended to be affixed to surfaces forms the container for affixing or securing means of mechanical and adhesive nature.

15 The object of the invention is to provide a self-contained package including sheet or strip material, the mechanical securing appliances, and adhesive material for cementing the joints.

Another object of the invention is to so construct a package or roll of material that affixing or securing means may be safely contained therein.

20 Another object of the invention is to so construct a package comprising a roll of material having a bore and closures for the bore that the closures may be adjustably secured therein without obstructing the central portion of the bore, whereby the contents of the bore may occupy such central portion.

25 The invention consists of a roll of sheet or strip material adapted to be unrolled and having a cavity in the nature of a bore and closures separably secured in the end portions of the cavity and preferably connected together by a wire or equivalent connecting means extending along near the wall of the bore and adjustably secured to one of the closures.

30 The invention also consists of a roll of material having an open center or bore, plugs fitting the ends of the bore, and means in the nature of a wire attached to one of said plugs and extending through said bore near the wall thereof and adjustably fastened to the outer portion of the other of said plugs.

35 The invention also consists in such other novel features of construction and combina-

tion of parts whereby the objects of this invention may be carried into effect, as shall hereinafter be more fully described, and pointed out in the claims.

In the drawings, Figure 1 represents a view 55 of a roll of roofing or building paper partially cut away to show the open center or bore, the packages supposed to respectively contain nails, tin caps for the nails, and the adhesive material for cementing the joints of the paper, also illustrating the preferred form of closures for the open ends of the bore and the securing-wire fixed to such closures. Fig. 2 represents an enlarged view of the closures and the preferred means for securing them. 65

Similar numerals of reference designate corresponding parts throughout.

Roofing or building material of this nature is applied by lapping the cemented edges of the paper and securing them by nails driven 70 through tin or other thin metal caps and then coating the seams with cement. In order to insure reliable work, special nails and tin caps are required and a special quality of cement is essential, and it is important that these be 75 supplied with the paper as a complete outfit for the work to be accomplished. In carrying this invention into practice it has been our desire to supply this complete kit or outfit without change in the outer cylindrical 80 shape of the package and in such manner that the rolled material forms a protecting-wall for the vessel in which the necessarily fluid cement is contained, and in the preferred form we provide devices for securing the several packages from movement. 85

As illustrating the structure in its preferred form and method of constructing this package, 5 represents a roll of roofing or other paper or material wound upon itself and having the open center or bore 6. To one end of the tapering plug 7, which is adapted to tightly fit in the end of the bore 6, we secure the wire 8 or its equivalent by means of the staples 9 and 10, and passing the free end of the wire 90 through the bore we secure this plug in one end thereof. The packages having been previously prepared, we now place the package 11 of tin caps next to the plug 7, then insert 95 the cylindrical can 12 of cement, which closely 100

fits the bore, and placing the package 13 of nails on the top of the can 12 we insert the plug 14 in the open end of the bore and force the same inward sufficiently to slightly crowd the packages 11, 12, and 13 together to prevent undue movement thereof, the free end of the wire 8 being finally drawn tightly over the top of the plug 14 and secured by means of the staples 15 and 16, any suitable wrap being placed about the whole. The method of opening the package is apparent from the construction.

It is naturally evident that the prime object of the invention is the inclosing within the material 5 of the packages 11, 12, and 13, and particularly of protecting the package or can 12 of cement from such injury as would result in leakage and the resultant damage from the fluid cement. This desirable object is made possible by the nature of the closures and their connecting means, whereby the central portion of the bore is unobstructed by the connecting means to receive the packages, the connecting wire or means extending along near the wall of the bore and being positively held from movement toward the axis of the bore by the insertion of the can 12.

The separably-adjustable plugs may be secured in place relatively to each other by other means than those described; but it is believed that the simplest and most efficient means is that shown and preferred by us—namely, a wire or equivalent connection between the closures, so arranged that the central portion of the bore is left free and unobstructed.

Having thus described our invention, we claim as new and desire to secure by Letters Patent—

1. A package comprising a roll of material adapted to be unrolled and having a central bore, plugs adjustably fitted into the ends of the bore, and a wire connecting the plugs and adjustably secured to the outer portion of one plug and extending along the wall of the bore.

2. A package comprising a roll of material adapted to be unrolled and having a central bore, plugs adjustably fitted into the ends of the bore, and a wire adjustably secured to the outer surfaces of the plugs and extending between the peripheries of the plugs and the wall of the bore.

3. A package comprising a roll of material adapted to be unrolled and having a central bore, tapering plugs adjustably fitting into the ends of the bore, and a wire bent over and adjustably secured to the outer ends of the plugs and extending between the peripheries of the plugs and the wall of the bore. 55 60

4. A package comprising a roll of material adapted to be unrolled and having a central bore, a wire adjustably secured to the outer surfaces of the plugs and extending between the peripheries of the plugs and the wall of the bore, and staples secured to said surfaces of the plugs and in engagement with the wire. 65

5. A package comprising a roll of material adapted to be unrolled and having a central bore, closures for the ends of the bore, and a wire connecting the two closures and adjustably secured to one of said closures and extending along the wall of the bore. 70

6. A package comprising a roll of material adapted to be unrolled and having a central bore, closures for the ends of said bore, a wire connecting the closures and adjustably secured to one of said closures and means contained within the bore to positively hold the wire approximately against the wall of the 80 bore. 75

7. A package comprising a roll of material adapted to be unrolled and having a central bore, closures for the ends of the bore, and a wire connecting said closures and adjustably secured to one of them, said closures being constructed to support the wire, when adjusted, along the wall of the bore to leave the center unobstructed. 85

8. A package comprising a roll of material adapted to be unrolled, and having a central bore; separate closures inserted, one in each end of said bore, and adjustable in distance from each other; and means, adjustable in relation to the inserted closures, for securing 95 said closures in place, whereby packages may be safely held in the cavity between the closures. 90

In testimony whereof we affix our signatures in presence of two witnesses.

CHARLES S. BIRD.
JOHN B. HANSCOM.
